UNITED STATES PATENT OFFICE.

ANTON M. KROCEK, OF CHICAGO, ILLINOIS.

BIRDCAGE-BASE CONSTRUCTION.

Application filed August 5, 1924. Serial No. 730,254.

This invention relates to a bird cage base construction and has for its primary object a construction whereby the bottom is more effectively held in place and more readily disconnected when desired.

An object of the invention is the construction of a removable base which will be positively held against accidental displacement.

A feature of my invention is the novel manner of shaping the bottom and associating same with the ring so that a very substantial construction is attained.

With these and other objects in view the invention will be better understood from the following detailed description taken in connection with the accompanying drawings wherein:

Fig. 1 is a sectional view of my improved base construction.

Fig. 2 is a bottom plan view partly in section of the removable bottom member embodied in the invention.

Fig. 3 is a detail sectional view on the line 3—3 of Fig. 2.

Again referring to the drawing illustrating one of the many constructions of my invention the numeral 1 designates a base ring having oppositely disposed recesses 2 depressed therein. The removable bottom 3 is stamped to provide a plurality of trays 4 and marginal flange 5 having snug sliding engagement with the interior surface of the ring. Oppositely disposed leaf springs 5^b are fixed to the bottom and carry lugs or catches 6. These catches 6 are slidable through openings 6' formed in the marginal flange 5 as shown in Fig. 2 for snapping engagement into the recesses 2. Aligned control rods 7 are slidably supported on the bottom member by means of brackets 7' and are connected to the springs for retracting the catches from the recesses and these rods have their adjacent ends bent into finger grips 8.

As illustrated in Fig. 1 of the drawing the ring 1 has an inwardly curved portion 1' adapted for engagement with a similar inwardly curved portion 2' formed on the marginal flange 5 below the top edge 5' thereof.

This construction is such that when the base 3 is inserted in operative position with respect to the ring the curved portions 1' and 2' serve to properly locate the catches 6 for snapping engagement into the recesses 2.

From the foregoing description taken in connection with the accompanying drawing it will be apparent that by engaging the finger grips and forcing same towards each other the springs will be readily retracted for moving the catches out of engagement with the recesses for allowing the ready removal of the bottom. To place the bottom in position it is only necessary to force the bottom upwardly into position as the snap action of the catches will bring about proper engagement to lock the bottom in position.

It is, of course, to be understood that the bottom may be given other shapes than illustrated and various other snap devices may be utilized for bringing engagement between the bottom and the flange, therefore, I do not desire to be limited in any manner except as set forth in the claims hereunto appended.

Having thus described my invention what I claim is—

1. A bird cage base construction including a base ring having outwardly depressed portions providing opposite recesses, a bottom member having a marginal flange adapted for slidable insertion in the base ring, and means carried by the bottom member for releasably locking the bottom member within the base ring, said means including oppositely disposed resilient members carried by the bottom member and provided with projecting portions adapted for snapping engagement with the recesses.

2. A bird cage base construction including a base ring having outwardly depressed portions providing opposite recesses, a bottom member having a marginal flange adapted for slidable insertion in the base ring, means carried by the bottom member for releasably locking the bottom member within the base ring, said means including oppositely disposed resilient members carried by the bottom member and provided with projecting portions adapted for snapping engagement with the recesses, and means for disengaging the projecting portions from the recesses, said means including aligned members supported for slidable movement on the bottom member and having end portions connected to the resilient members and having adjacent end portions angled to provide finger gripping portions.

3. A bird cage base construction including a base member having an inwardly

curved portion, a base ring slidably receiving the base member and having an inwardly curved portion in abutment with the inwardly curved portion of the base member and having opposite depressed portions providing recesses, and means carried by the base member for releasably locking the base member within the base ring, said means including catch members adapted for engagement in the recesses and resilient means for normally holding the catch members within the recesses.

4. A bird cage base construction including a base member having an inwardly curved portion, a base ring slidably receiving the base member and having an inwardly curved portion in abutment with the inwardly curved portion of the base member

and having opposite depressed portions providing recesses, means carried by the base member for releasably locking the base member within the base ring, said means including catch members adapted for engagement with the recesses and resilient means for normally holding the catch members within the recesses, and means for disengaging the projecting portions from the recesses, said means including aligned members supported for slidable movement on the bottom member and having end portions connected to the resilient members and having adjacent end portions angled to provide finger gripping portions.

In testimony whereof I affix my signature.

ANTON M. KROCZEK.
